VERTICAL-AXIS ROTARY LOOP-TAKER
FOR SEWING MACHINESJohn G. G. Batting, Westport, Conn., assignor to
The Singer Manufacturing Company, Elizabeth, N. J., a corporation of New Jersey

Application March 6, 1942, Serial No. 433,600

6 Claims. (Cl. 112—256)

This invention relates to lubricating means for sewing machine loop-takers, and more particularly to loop-takers of the vertical-axis rotary hook type in which a thread-carrier is journaled in a raceway of and is restrained against rotation with the loop-taker.

The primary object of the invention is to provide a sewing machine with simple means designed to insure adequate lubrication of the thread-carrier raceway of a vertical-axis rotary loop-taker during the operation of the sewing machine and to obviate excess lubrication of said raceway when the sewing machine is out of operation and when the machine is thereafter brought into operation.

Other and more specific objects of the invention will be apparent from the following description and claims.

The invention consists in the combination of lubricant pumping and feeding means for supplying lubricant to the raceway of a vertical-axis rotary loop-taker, as hereinafter described in connection with the accompanying drawings, in which:

Fig. 1 is an enlarged vertical section, partly in front side elevation, of the stitch-forming mechanism of a sewing machine containing one embodiment of the present improvement, the section being taken lengthwise of the machine in a plane containing the axis of rotation of the rotary loop-taker. Fig. 2 represents a fragmentary vertical section similar to Fig. 1 and illustrates a modified form of lubricant-pumping means. Fig. 3 represents a horizontal section of the modified lubricant-pump on substantially the line 3—3 of Fig. 2. Fig. 4 also represents a fragmentary vertical section similar to Fig. 1 and illustrates another modified form of lubricant-pumping means. Fig. 5 represents a horizontal section of the further modified lubricant-pump on substantially the line 5—5 of Fig. 4.

Referring to Fig. 1 of the drawings, the sewing machine has the usual work-supporting bed-plate 10 provided with slide-plates 11 and 12 disposed at opposite sides of a throat-plate 13 having feed-slots 14. Operating through the feed-slots 14 of the throat-plate is a feed-dog 15 provided with apertures 16 to receive the vertically and laterally actuated needles 17 of a compound or combined needle and feed-dog work-advancing mechanism which may be of any usual or suitable construction. The feed-dog 15 is opposed by a spring-depressed presser-foot 18 having clearance slots 19 for the needles 17. While the present improvement is in part illustrated as embod-

ied in a sewing machine having two work-feeding needles, it is to be understood that the invention is not limited to any particular form of feeding mechanism or to the number of needles employed.

Disposed below the work-support and complementary to the right hand needle 17 in the formation of lock-stitches is a rotary loop-taker 20. The loop-taker 20 is of the rotary hook type having its axis of rotation substantially parallel to the needle 17 and substantially normal to the plane of the work-support 10, 11 and 12. The loop-taker 20 has the usual upwardly open cup-shaped body of which the cylindrical side wall is provided with a needle-thread loop-seizing beak 21 and, internally, with a horizontally disposed raceway 22.

Journalized in the raceway 22 of the loop-taker 20, as illustrated in Fig. 1 of the drawings, is a peripheral bearing-rib 23 of a thread-carrier 24. The thread-carrier is restrained against rotation with the loop-taker 20, and to this end the thread-carrier is provided with a nose 25 in engagement with a stop-lug 26 depending from the throat-plate 13.

The loop-taker 20 is carried by the upper end of a vertically disposed loop-taker shaft 27 which is preferably integral with the bottom wall 28 of the loop-taker body. At its upper end, directly below the bottom wall 28 of the loop-taker body, the loop-taker shaft 27 is enlarged or otherwise provided with an actuating eccentric 29. The eccentric 29 is embraced by the suitably apertured end of a short pitman 30, of which the opposite end is connected in any usual or suitable manner with conventional means (not shown), for slightly oscillating the thread-carrier 24 in a direction opposite to the direction of rotation of the loop-taker 20.

The loop-taker shaft 27 is rotatably journaled in the usual supporting bracket 31 suitably secured upon a bushing 32 carried by a lug 33 depending from the bed-plate 10; said bushing being apertured to provide a bearing for a horizontally disposed rotary actuating or bed-shaft 34 extending lengthwise of the bed-plate 10.

The loop-taker supporting bracket 31 is formed with vertically spaced upper and lower bearing-lugs 35 and 36 which are respectively provided with apertures 37 and 38 in vertical alinement. Disposed in the aperture 37 of the upper bearing-lug 35 is a ball-bearing 39 in which the loop-taker shaft 27 is rotatably journaled. A washer 40 is preferably interposed between the ball-bearing 39 and the eccentric 29 of the loop-taker shaft 27 to minimize friction; said washer preferably

having its lower face circumferentially recessed to receive a ring 41 of felt or similar lubricant-conducting material. Threaded into the upper bearing lug aperture 37 from the under side thereof is a nut 42 which locates the ball-bearing 39 in said lug-aperture 37.

The loop-taker shaft 27 is similarly journaled in the lower bearing-lug 36 of the loop-taker bracket 31. To this end, the lower bearing-lug aperture 38 is provided with a ball-bearing 43 which is vertically located in set position by a nut 44 suitably apertured to provide clearance for the shaft 27 and threaded into the bearing-lug 36 from the under side thereof. A washer 45 overlies the lower ball-bearing 43 and is circumferentially recessed in its lower face to receive a ring 46 of felt or similar lubricant-conducting material. The nuts 42 and 44 may be suitably secured to the bracket-lugs in the desired set positions of the loop-taker shaft ball-bearings.

Secured to the loop-taker shaft 27, by a set-screw 47, is the hub of a driven spiral-gear 48 suitably rotated from the bed-shaft 34 so that the loop-taker 20 rotates twice for each complete endwise reciprocation of the needle 17. The hub of the spiral-gear 48 is disposed between the nut 42 of the upper bearing-lug and the washer 45 overlying the lower ball-bearing. The loop-taker shaft 27 is therefore restrained against endwise movement in the supporting bracket 31.

The bottom wall 28 of the loop-taker 20 is axially provided in its upper face with an annular recess 49, and said recess 49 is counterbored to receive a closure-disk 50 which is preferably substantially flush with the inner or upper face of said bottom wall 28. The bottom wall 28 of the loop-taker is also provided with a duct 51 extending radially outwardly from the recess 49 and suitably plugged at its outer end. The radial duct 51 is open to the lower end of a generally vertical duct 52 provided in the cylindrical side wall of the loop-taker 20. The upper end of the side wall duct 52 is open to the loop-taker raceway 22 and the lower end of said duct 52 is suitably sealed or plugged below the radial duct 51. The connected ducts 51 and 52 together form a lubricant-conduit connecting the loop-taker recess 49 with the raceway 22.

The loop-taker shaft 27 has a longitudinal axial bore 53 extending throughout the length of the shaft, whereby said bore 53 is open at the lower end of the shaft and is open at its upper end to the loop-taker recess 49 which, preferably, is diametrically larger than the shaft-bore 53. The lower end portion of the loop-taker shaft 27 is externally provided with a spiral lubricant-impelling thread 54.

Suitably attached to a flange 44' of the nut 44 is the rim of a cup 55, depending from and providing a lubricant-reservoir 56 below the nut 44. The bottom-wall 57 of the cup 55 is provided with a cylindrical pump-cavity 58 having its side wall concentric with the axis of rotation of the shaft 27; the bottom wall 57 being externally cut away or slabbed to provide for employment of a wrench when applying the nut 44. The threaded portion of the nut 44 therefore comprises, in effect, a nipple of the lubricant reservoir 56.

The threaded portion 54 of the shaft 27 extends downwardly into the pump-cavity 58 of the lubricant-reservoir and the thread 54 is directionally spiralled to function during the operation of the machine to pump lubricant downwardly toward the lower end of the shaft. The

lubricant is thereby forced upwardly through the open bore 53 of the shaft 27 and is supplied to a lubricant-feeding wick 59 disposed in the upper portion of the shaft-bore 53 for rotation with the shaft; the lower end of said wick preferably being disposed a substantial distance above the level of the supply of lubricant in the reservoir 56, and the upper end of the wick 59 extending into the loop-taker recess 49. Inasmuch as the wick 59 rotates with the shaft 27, the lubricant is thrown off from the upper end of the wick, during the operation of the machine, into the annular recess 49 of the loop-taker. The lubricant is thereby supplied to the loop-taker ducts 51 and 52 connected to said recess, and which ducts deliver the lubricant to the thread-carrier raceway 22 of the loop-taker.

While the lubricant is therefore pumped from the reservoir 56, the wick 59 comprises lubricant-feeding means which controls the delivery of the pumped lubricant to the raceway of the loop-taker. The cylindrical wall of the pump-cavity 58 is spaced from the shaft-thread 54 suitably to obtain the desired pumping effect. Preferably, the pumping force is such as merely to insure that the lubricant reaches the lower end of the wick 59. However, under certain conditions it may be preferred to pump the lubricant with sufficient force to supplement the capillary lubricant-feeding action of the wick 59, in which event the pump-activity is proportioned accordingly.

As the pumping of the lubricant ceases upon stopping of the machine, no lubricant is supplied to the wick 59 when the machine is idle. This arrangement obviates any possibility of the wick becoming so saturated with lubricant, while the machine is idle, as to deliver an excess of lubricant when the machine is again started in operation.

In the modified form of the improvement illustrated in Figs. 2 and 3 of the drawings, the elongated or slabbed portion 60 of the lubricant-reservoir bottom wall 57 is provided with a pump-cavity 61 having the generally cylindrical side wall thereof merging in scroll fashion into a small segmental recess 62, thereby forming a scroll-shaped pump-cavity. The modified loop-taker shaft 63 likewise has a longitudinal bore 64 provided in its upper portion with a wick 65; said bore being connected, as before, with the thread-carrier raceway of the loop-taker.

The loop-taker shaft 63 has a diametrically reduced lower end portion 63', extending downwardly through the reservoir 56 and into the pump-cavity 61; said shaft being peripherally provided, within said cavity, with lubricant-impelling teeth 66, thereby to form a centrifugal pump. The teeth 66 are shaped to agitate the lubricant within the pump-cavity in directions substantially tangential to the shaft 63 upon rotation of said shaft, thereby to induce circular movement of the lubricant under pressure into the constricted recess 62 of the pump-cavity 61. As upward movement of the lubricant, which is under pressure in the pump-cavity recess 62, is opposed by the lubricant-supply in the reservoir, the lubricant is forced downwardly through a duct 67 provided in the bottom wall of the pump-cavity 61 and disposed in vertical alignment with the recess 62.

The duct 67 opens into a conically constricted valve-portion 68 of a horizontally extending transverse duct 69 leading to the open lower end 70 of a vertically disposed tube 70 fixed in an aper-

ture in the bottom wall of the pump-cavity 61; said tube extending upwardly into the shaft-bore 64 into proximity to the lower end of the wick 65. The tube 70, of which the upper end is disposed a substantial distance above the lubricant-reservoir, is preferably spaced from the shaft 63 to provide drainage clearance in the shaft-bore, externally of said tube, for excess lubricant supplied by the lubricant-pump. Threaded into the wall 60 is a valve-screw 71 having a conically pointed end adjustably extending into the valve-portion 68 of the duct 69, thereby to provide for controlling the effective action of the pump.

It will be understood, of course, that when the machine is idle there is a column of lubricant in the tube 70 equal in height to the lubricant-supply in the reservoir. In the operation of the machine, the shaft 63 is rotated at high speed, whereby the described centrifugal pump forces the lubricant upwardly in the tube 70 and supplies lubricant to the wick 65. Excess lubricant not absorbed by the wick 65 drains through the bore 64 of the loop-taker shaft 63. When the machine is out of operation, no lubricant is supplied to the wick 65, whereby excess saturation of the wick is obviated at the beginning of the operation of the machine.

In the further modified form of the improvement, illustrated in Figs. 4 and 5 of the drawings, the bottom wall 72 of the lubricant-reservoir 73 is provided in the underside thereof with an annular recess forming a vertical cylindrical pump-cavity 74. A bottom closure-plate 75 for the pump-cavity is attached, as by screws 76, to the under side of the bottom-wall 72 and sealed by a suitable gasket 77. The top wall 78 of the pump-cavity 74, which wall is also the bottom wall of the reservoir 73, is provided with an opening 79 connecting the lubricant-reservoir 73 with the pump-cavity.

The vertically disposed loop-taker shaft 80 extends downwardly through the reservoir 73 and through the connection-opening 79 into the pump-cavity 74; said shaft having a longitudinal bore 81 provided in the upper portion thereof with a lubricant-feeding wick 82 connected with the thread-carrier raceway of the loop-taker, as illustrated in Fig. 1. Extending upwardly into the bore 81 of the loop-taker shaft and preferably into proximity to the lower end of the wick 82 is a stationary tube 83 spaced from the loop-taker shaft 80; the tube 83 being fixed in an aperture of the bottom closure-plate 75.

Carried by the lower end of the loop-taker shaft 80, within the pump-cavity 74, is a centrifugal lubricant-impeller 84 having a plurality of substantially radial vanes extending into close proximity to the cylindrical side wall of the pump-cavity. Opening into the pump-cavity 74, radially thereof, is a horizontal duct 86 connected by a conical valve-opening 87 with a vertical duct 88. Connected with the duct 88 is one end of an angular duct 89 provided in the closure-plate 75; the opposite end of said duct 89 being open to the lower end of the stationary tube 83. A valve-screw 90 is threaded into the wall 72 and has a conically pointed end adjustably extending into the valve-opening 87, thereby to provide for controlling the effective action of the pump.

In the operation of the machine, the rotating impeller 84 develops a lubricant pressure sufficient to supply lubricant to the wick 82, the efficiency of the pump being regulatable by adjustment of the valve-screw 90. Excess lubri-

cant discharged from the upper end of the tube 83 is free to drain downwardly in the shaft-bore 81. This modification likewise has the inherent advantage of obviating excess saturation of the wick 82 when the machine is out of operation.

Having thus set forth the nature of the invention what I claim herein is:

1. In a sewing machine having a horizontally disposed work-support, a vertical-axis rotary shaft disposed substantially normal to said work-support and having a longitudinal bore open at the lower end of said shaft, a loop-taker carried by the upper end of said shaft and having a thread-carrier raceway, lubricant-conducting connections between said bore of the rotary shaft and said raceway, lubricant-supply means including a cup having a pump-cavity, said cup having the wall thereof apertured to provide a lubricant-discharge conduit leading from said pump-cavity and connected with said shaft-bore endwise of said shaft, lubricant-pump means carried by the lower end of said shaft and extending into said pump-cavity, and means for controlling the delivery to said raceway of lubricant supplied to said shaft bore by said pump means.
2. In a sewing machine having a horizontally disposed work-support, a vertical-axis rotary shaft disposed substantially normal to said work-support and having a longitudinal bore open at the lower end of said shaft, a loop-taker carried by the upper end of said shaft and having a thread-carrier raceway, lubricant-conducting connections between said bore of the rotary shaft and said raceway, lubricant-supply means including a cup having a pump-cavity, lubricant-pump means carried by the lower end of said shaft and extending into said pump-cavity, a lubricant-pump discharge conduit leading from said pump-cavity, said conduit including a tube extending upwardly from said cup into said bore of the rotary shaft in spaced relation to said shaft, and means for controlling the delivery to said raceway of lubricant supplied to said bore of the rotary shaft by said pump means.
3. In a sewing machine, a vertical-axis rotary shaft having a longitudinal bore open at the lower end of said shaft, a loop-taker carried by the upper end of said shaft and having a thread-carrier raceway, lubricant-conducting connections between said bore of the rotary shaft and said raceway, lubricant-supply means including a cup having a pump-cavity, lubricant-pump means carried by the lower end of said shaft and extending into said pump-cavity, a lubricant-pump discharge conduit leading from said pump-cavity and including a tube extending upwardly into said bore of the rotary shaft, valve-means in said discharge conduit, and a lubricant-feeding wick disposed in the upper end portion of said shaft bore above the upper end of said tube.
4. In a sewing machine, a vertical-axis rotary shaft having a longitudinal bore open at the lower end of said shaft, a loop-taker carried by the upper end of said shaft and having a thread-carrier raceway, lubricant-conducting connections between said bore of the rotary shaft and said raceway, lubricant-supply means including a cup having a pump-cavity, centrifugal pump means carried by the lower end of said shaft and extending into said pump-cavity, a lubricant-pump discharge conduit formed in a wall of said cup and leading from said pump-cavity, said conduit being connected with the bore of said shaft endwise of the shaft, and a metering screw threaded into said wall to extend into said conduit.

5. In a sewing machine having a horizontally disposed work-support, a vertical-axis rotary shaft disposed substantially normal to said work-support and having a longitudinal bore open at the lower end of said shaft, a loop-taker carried by the upper end of said shaft and having a thread-carrier raceway, lubricant - conducting connections between said bore of the rotary shaft and said raceway, a lubricant-supply reservoir having a pump-cavity, said shaft having the lower portion thereof extending through said reservoir and into said pump-cavity, centrifugal pump means carried by said shaft within said pump-cavity, a lubricant-pump discharge conduit leading from said pump-cavity and connected with said shaft bore endwise of said shaft, and a lubricant-feeding wick disposed in said shaft bore entirely above the level of the lubricant-supply in said reservoir.

6. In a sewing machine, a vertical-axis rotary

shaft having a longitudinal bore open at the lower end of said shaft, a loop-taker carried by the upper end of said shaft and having a thread-carrier raceway, lubricant-conducting connections between said bore of the rotary shaft and said raceway, a lubricant-supply reservoir provided at the under side thereof with a pump-cavity, said pump-cavity having a removable bottom closure-plate and said shaft having the lower portion thereof extending through said reservoir and into said pump-cavity, a tube extending upwardly from said closure-plate into the bore of said shaft, centrifugal pump means carried by said shaft within said pump-cavity, a lubricant-pump discharge conduit leading from said pump-cavity and connected with said tube, valve means in said discharge conduit, and a lubricant-feeding wick disposed in the upper end portion of said shaft bore above the upper end of said tube.

JOHN G. G. BATTING.
